BY *J. W. FISH*
Watson E. Coleman
ATTORNEY.

UNITED STATES PATENT OFFICE.

JOHN N. PRISK, OF JOHNSTOWN, PENNSYLVANIA.

BUTCHERING IMPLEMENT.

Application filed July 7, 1923. Serial No. 650,129.

To all whom it may concern:

Be it known that I, JOHN N. PRISK, a citizen of the United States, residing at Johnstown, in the county of Cambria and State 5 of Pennsylvania, have invented certain new and useful Improvements in Butchering Implements, of which the following is a specification, reference being had to the accompanying drawings.

10 This invention relates to butchering implements and more particularly to a stunning hammer for stunning steers and the like prior to the sticking operation.

An important object of the invention is 15 to provide an arrangement whereby uncertainty as to the stunning of the animals at a single blow is removed.

A further object of the invention is to provide a device of this character which is adjustable thereby permitting its use with animals of different sizes.

A further object of the invention is to provide a device of this character which is simple in its construction and arrangement, durable in service and a general improvement 25 in the art.

These and other objects I attain by the construction shown in the accompanying drawings, wherein for the purpose of illustration is shown a preferred embodiment of my invention and wherein:

Figure 1 is a side elevation of butchering apparatus constructed in accordance with my invention;

25 Figure 2 is a front elevation of the head stop employed;

Figure 3 is a section on the line 3—3 of Figure 1;

Figure 4 is a vertical sectional view 40 through the apparatus taken at right angles to the view shown in Figure 3; and

Figure 5 is a horizontal sectional view therethrough.

Referring now more particularly to the drawings, the numeral 10 designates a frame including vertically disposed angle guides 11, these angle guides receiving the corner posts 12 of a rectangular horizontally disposed platform 13. The longer sides of the 45 platform 13 are provided at their side edges with longitudinally extending braces 14. Beneath the platform 13, and more particularly beneath the ends of the platform in alignment with these longitudinally extending braces 14, guides 15 are provided at each 50 side of the platform and in alignment with

the angle guide 11 of the frame 10. Extending transversely of the bottom of the frame 13 and supported in bearings 16 is a shaft 17 provided in alignment with each aligned 60 pair of guides with a lever 18 which is secured to the shaft at its central portion and which has at its ends links 19 connecting the same with brake elements 20 slidably disposed in the guides 15. At one 65 end the bearing 16 of the shaft is formed in a plate provided at its upper surface with an arcuate edge which is notched, as at 21, for coaction with a catch 22 carried by a lever 23 secured to the shaft, so that 70 the shaft may be rotated and held in adjusted position. It will be obvious that by rotation of the shaft the brake elements 20 may be projected for engagement with the guides or withdrawn from such engagement. 75

One end of the platform 13 is provided with a transverse member 24 from which projects a cylindrical member 25 having the end thereof next adjacent the platform closed, as indicated at 26, and provided with 80 an axially disposed bearing 27. Through this bearing is directed the shank 28 of a hammer member 29, the engaging end of which is provided with a blunt face 30 having a restricted area. Between the head 29 85 and the closed end 26 of the tubular member 25 a spring 31 is disposed normally urging the head outwardly from the closed end and accordingly from the platform 13. This outward movement is limited by a pin 32 90 which extends transversely of the shank 28 and engages against the inner face of the closed end 26.

Arranged upon the adjacent faces of the reinforcing members 14 are the sides of 95 guide members 33 having aligned longitudinally extending slots 34 receiving the ends of a pin 35 directed through the inner end of the shank portion 28. Above the pin 35 a shaft 36 is mounted in bearings carried by 100 the side members 14 and extends transversely of the platform 13 and is provided with a pair of spaced cam members 37, the facets 38 of which are adapted to engage and withdraw the shank and hammer against the action of the spring 31 and the suddenly released cam, permitting the shank and hammer to be rapidly advanced under the influence of the spring 31 to thereby provide a sharp blow of the hammer 29. This shaft 110 may be driven in any suitable manner.

In the present instance I have disclosed

the shaft as provided upon one end with a pulley 39, and upon the opposite end with a gear wheel 40. Extending transversely of the platform 13 is a second shaft 41 having at one end a pinion 42 engaging the gear wheel 40 and at its opposite end a pulley 43 for engagement with a belt. The shaft is provided at one end thereof with a crank handle 44 whereby it may be rotated. 10 Thus the shaft 36 may be rotated either by rotating the handle 44, thus driving the shaft through the pinion 42 and gear 40, or by applying a belt directly to the pulley 39 thereof, or by applying a belt to the 15 pulley 43 of the shaft 41. It will, of course, be obvious that in conjunction with an apparatus of this character a stanchion 45 for holding the animal with its head in the proper position must be provided. In the 20 present instance I have simply illustrated a stanchion including a relatively fixed block 46 and a slideable block 47, the blocks having coacting notches combining to form a neck receiving opening 48. In order that 25 the stocks may be accommodated to animals of various sizes the relatively stationary member thereof is made vertically adjustable in some suitable manner by a pin, in the present instance shown as held in position by pins 49 extending through the stationary members 50 of the stocks and selectively engaging in one of a plurality of openings 51 formed in the stationary member. In order to provide for adjustment of the platform 13 to bring the hammer 29 into proper alignment with the head of the animal engaged in the stocks elevating apparatus of any suitable character is provided, in the present instance I have 30 shown this as consisting of a shaft 52 rotatably mounted upon the angle guides 11 at one end of the frame and provided with a crank 53 whereby it may be rotated. Upon the shaft a ratchet 54 is mounted coacting 35 with a pawl 55 carried by the frame. This pawl normally prevents rotation of the shaft in one direction. About the shaft is wound a flexible element 56 which passes about pulleys 57 and has an end having branches 40 58, one of which is secured to the upper end of each of the vertical standards 12 at the corners of the frame 13. It will be obvious that by properly operating the shaft the desired level may be obtained and the 45 platform held in such adjusted position either by the brake members 20 or by the pawl and ratchet mechanism of the shaft. It will be obvious that upon rotation of the shaft the hammer 29 will be rapidly 50 reciprocated and since the head of the animal is held against movement will engage

thereagainst the same spot at each operation. It will furthermore be obvious that the structure hereinbefore set forth is capable of some change and modification without in any manner departing from the spirit of my invention and I accordingly do not limit myself to such specific structure except as hereinafter claimed. 65

I claim:

1. In combination, vertical guides, a platform vertically adjustable upon said guides, means for holding the platform in adjusted position, a hammer horizontally mounted upon the platform, means constantly urging said hammer in one direction, means for withdrawing the hammer against the first named means and suddenly releasing the same, and means for holding an animal with head thereof in position for engagement by said hammer. 75

2. In butchering apparatus, vertical guides, a horizontal platform vertically adjustable in said guides, means for holding the platform in adjusted position, a horizontally disposed sleeve carried by said platform and having one end thereof formed to provide a guide, a hammer having a shank slidably disposed within said guide, a spring surrounding said hammer between the head thereof and said guide, means for withdrawing the hammer against the action of the spring and suddenly releasing the same, and means for maintaining the animal with its head in alignment with said hammer and in position to be engaged by the hammer when extended by said spring. 85

3. In butchering apparatus, vertical guides, a horizontal platform vertically adjustable in said guides, means for holding the platform in adjusted position, a horizontally disposed sleeve carried by said platform and having one end thereof formed to provide a guide, a hammer having a shank slidably disposed within said guide, a spring surrounding said hammer between the head thereof and said guide, means for withdrawing the hammer against the action of the spring and suddenly releasing the same, means for maintaining the animal with its head in alignment with said hammer and in position to be engaged by the hammer when extended by said spring, said means for withdrawing and releasing said hammer comprising a pin directed through the shank of the hammer, a shaft rotatably mounted upon the platform above said pin, cams carried by the shaft and engaging with said pin, and means for rotating said shaft. 100

In testimony whereof I hereunto affix my 105 signature.

JOHN N. PRISK.
